UNITED STATES PATENT OFFICE.

SARAH LIPTON, OF BROOKLYN, NEW YORK.

GARMENT.

1,110,304.

Specification of Letters Patent. Patented Sept. 8, 1914.

Application filed April 1, 1914. Serial No. 328,723.

To all whom it may concern:

Be it known that I, SARAH LIPTON, a citizen of the United States, residing at Brooklyn, in the county of Kings and State of New York, have invented certain new and useful Improvements in Garments, of which the following is a specification.

The object of the invention is to provide for the simple and convenient adjustment of buttons or other fastening devices to allow for a corresponding adjustment of the operative dimensions of a garment, whereby, for example, a waist or similar body-enveloping garment adapted for a child of a given size, can subsequently be adapted to an increased size, due to growth, and whereby such adjustment may be accomplished to adapt a garment of the indicated characteristics to be made in stock sizes, thus economizing in the amount of stock required to be carried by the dealer, in order to supply the demands of the trade.

With this general object in view, the invention consists essentially in providing a garment with buttons or other fastening devices adapted to be readily located in relation to a plurality of seats disposed in series in the direction of expansion or girth enlargement or increase of the garment, such buttons or other fastening devices being mounted upon or carried by runners or guides located respectively adjacent to and parallel with each series of seats, whereby it becomes possible readily to unseat the button or other fastening device and reseat it in a position to either enlarge or diminish the girth of the particular portion of the garment effected thereby. By providing, in coöperation with such adjustable buttons or other fastening devices, a series of buttonholes or other elements to engage said fastening devices, the possibilities of the invention, so far as increasing the range of utility and adaptability of the garment, can be still further increased.

Further objects and advantages of the invention will appear from the following description thereof, it being understood that various changes in the form, proportions and minor details of the construction may be resorted to, without departing from the spirit of the invention.

In the drawings, illustrating a preferred embodiment of the invention, Figure 1 represents a child's garment in the nature of a waist or bodice, provided with fastening

devices mounted and arranged in accordance with the invention; Fig. 2 represents a detail of a portion of the same, showing the co-operating fastening elements engaged as 60 when the garment is in use; Fig. 3 represents a reverse view of the construction illustrated in Fig. 2; Fig. 4 represents a sectional view taken horizontally in the plane of one of the runners or guides for the button 65 shown therein.

In carrying out the invention, where buttons are designed to be used as the fastening devices, the garment, in the direction of the desired expansion or adjustment, is provided with series of seats which, in the illustrated embodiment, consist of slots or buttonholes 10, parallel with which are arranged flexible runners or guides 11 consisting, for example, of tapes terminally fastened to the garment, as at 12 (preferably in contact with the inner surface thereof, or beneath a protecting and concealing flap, which, however, is not necessary to the efficiency of the invention, and being a well 80 recognized expedient in tailoring and garment-making, is not illustrated). The buttons 13 or other fastening devices are threaded or otherwise mounted upon these runners or guides, the latter being sufficiently 85 full or loose to permit of projecting the button or fastening device through the desired seat or buttonhole 10, to expose the same at the outer side or face of the garment, where it is accessible for the ordinary manipulation in buttoning or otherwise fastening the garment through the coöperation therewith of the buttonholes 14, or other elements which may be employed as the complementary fastening means. 95

It will be obvious that the adjustable element of the complementary fastening devices may be arranged in either of several positions in the direction of the desired expansion or adjustment of the garment. The 100 provision of means for correspondingly varying the position of the other of such complementary means is not indispensable, but, as illustrated in the drawing, a still greater amplitude of adjustment and range 105 of adaptability can be secured by providing a plurality of buttonholes or other like elements corresponding and designed for co-operation with said adjustable fastening elements. Moreover, it should be noted that 110 this method of providing for adjustment of the dimensions of a garment may be ap-

plied not only to the portion thereof designed to encircle the body or trunk, but may also, as shown, be employed to vary the length or adjust the shoulder straps 15, as well as other features, the specific illustration of which is deemed unnecessary.

What is claimed as new is:

1. An expandible garment having complementary fastening devices for engagement with each other, one of which is movable relative to the garment in the direction of the desired expansion of the garment, a runner or guide for said movable fastening device attached to the garment and upon which said fastening device is slidably mounted, and a plurality of seats in the garment for respectively holding said movable fastening device in its different adjusted positions and in either of which it is adapted for engagement by the other complementary fastening device.

2. An expandible garment having complementary fastening devices, one of which is adjustable in the direction of the desired expansion of the garment, a tape terminally attached to the garment and upon which said fastening device is slidably mounted, and a series of seats or openings parallel with the tape, said seats being respectively adapted for holding said fastening device in its ad-

justed positions, and through which the same may be projected for engagement by the other complementary fastening device and may be withdrawn for adjustment.

3. An expandible garment having complementary fastening devices, one of which is adjustable in the direction of the desired expansion of the garment and which consists of a button, a slack tape terminally attached to one surface of the garment and having the button slidably mounted for adjustment thereon, and a plurality of slots or buttonholes arranged in the garment parallel with the tape for engagement with that portion of the tape which is adjacent to the fastening device at any desired adjustment thereof, and through which slots or buttonholes the button may be projected from the surface to which the tape is attached to the other surface, whereby said button is held for engagement by the other complementary fastening device, said slot or buttonhole being adapted to permit withdrawal of the button for readjustment.

In testimony whereof I affix my signature in presence of two witnesses.

SARAH LIPTON.
